CONTROL APPARATUS

Glenn T. McClure, McKeesport, Pa., assignor to
 The Westinghouse Air Brake Company, Wil-
 merding, Pa., a corporation of Pennsylvania

Application December 30, 1943, Serial No. 516,204

2 Claims. (Cl. 303—54)

This invention relates to control valve devices for use in fluid pressure control systems and has particular reference to a relay valve device of the self-lapping type for controlling the fluid pressure in such systems.

One object of the invention is to provide an improved relay valve device of the above type.

Another object of the invention is to provide a relay valve device having means for varying the ratio between the governing force developed by the control pressure and the balancing force developed in the relay valve mechanism.

Another object of the invention is to provide a relay valve device arranged to be controlled individually by fluid under pressure or jointly by fluid under pressure and by manually operative means.

Another object of the invention is to provide a relay valve device arranged to be controlled by fluid under pressure from a remote control station and including means manually operative from a local station for modifying or varying the pressure of fluid supplied by the device.

A still further object of the invention is to provide a fluid pressure responsive relay valve device embodying a controller, which is adjustable manually to vary the ratio between the control pressure and the controlled pressure.

Other objects and advantages will be apparent from the following more detailed description of the invention.

In the accompanying drawing Fig. 1 is a vertical sectional view of a relay valve device embodying the invention; and Fig. 2 is a sectional view of the relay valve device taken on the line 2—2 of Fig. 1.

The adjustable relay valve device 1 may comprise an upper casing section 2 and a lower casing section 3 which are secured together in any suitable manner. The section 3 has an opening at its right hand end as viewed in Fig. 1, which opening is closed by an end plate or cap 3a which is rigidly secured in any desired manner to the casing section 3.

Clamped between the casing sections 2 and 3 is a pair of laterally spaced flexible diaphragms 4 and 5 which are preferably of equal area.

At one side of the diaphragms 4 and 5 there is a chamber 6 which is in constant open communication with the atmosphere by way of a passage 8 provided in the end plate 3a. Contained in this chamber is a longitudinally extending control beam or lever 9 which, as will hereinafter more fully appear, is operative to control the operation of a self-lapping application and release valve

mechanism contained in the upper casing section 2.

One end of the control beam or lever 9 is pivotally connected, by means of a pin 12, to two laterally spaced arms of a link member 13 which link member is rockably mounted by means of a pin 14 between spaced lugs 15 and 16, projecting from the end plate 3a of the casing. The lower surface of the control lever or beam 9 is provided intermediate its ends with a bearing surface 18 which bears on the central portion 19 of a transversely extending bar 20 of round cross-section which serves as a fulcrum for said lever.

The bar 20 is mounted in a movable rectangular frame member 21 which is contained in chamber 6 and which may comprise a pair of spaced side pieces 23 and 24 which are joined together at opposite ends by inner and outer end pieces 25 and 26, respectively, the bar having its opposite ends mounted in suitable openings provided in the members 23 and 24, respectively. The side pieces 23 and 24 of the frame member slidably engage with guide members or bosses 27 and 28, respectively, which project inwardly from the opposite side walls of the casing, the boss 27 in the present embodiment of the invention being carried by a removable casing section or cap 3b and the boss 28 being carried by the casing section 3. The bosses 27 and 28 besides guiding the frame member 21 also extend across the ends of the bar 20 and thus prevent endwise movement of the bar relative to the frame member. From the foregoing description it will be seen that the frame member and bar 20 will be maintained against lateral movement relative to the casing section 3 by the lugs 27 and 28.

Rotatably mounted on the bar 20 are rollers 29 and 30 which are disposed one at each side of the lever 9. These rollers are maintained in place on the bar by collars 29a and 30a, respectively, which are secured in place on the bar by set screws, as shown. The rollers 29 and 30 engage and roll on a wear plate or track 31 carried by the bottom wall of the casing section 3.

The inner end piece 25 of the carriage 21 is provided intermediate its length with a stem 32 which projects to the exterior of the casing through a suitable bore 34 in an adjusting nut 35 which has screw-threaded connection with the casing section 3. The nut 35, exteriorly of the casing, is provided with an enlarged portion 36 having a central bore 37 of greater diameter than the bore 34.

Disposed in bore 37 and slidably mounted on the stem 32 is a spring seat 40. This spring seat

engages a shoulder 41 located at the junction of the bore 34 and counter bore 37, and is maintained against rotary movement relative to the stem 32 by means of a key 44 carried by the spring seat and engaging the side walls of a key way 45 provided in the stem.

Surrounding the stem 32 and interposed between and operatively engaging the spring seat 40 and a collar 47, carried by the stem is a spring 49, which collar is held on the stem by means of a lock member 47a which engages the stem. It will here be noted that the spring 49, at all times, urges a collar 59, provided on the inner end piece 25 of the lever 9, into engagement with the outer end 52 of the adjusting nut 35, so that rotary movement of the nut will effect longitudinal movement of the frame member 21 relative to the control lever or beam 9. Since the bar 20 is carried by the frame member 21 and engages the bearing surface 18 of the control beam or lever 9, thereby serving as a fulcrum for said lever, it will be obvious that any variation in the position of the frame member relative to the lever will result in variations in the leverage of the control beam or lever 9.

For rotating the nut 35 a handle 55 is provided which handle is rigidly clamped on the enlarged portion 36 of the nut 35, by means of a headed bolt 56 and a nut 57.

Contained in chamber 6 and engaging the lower side of diaphragm 5 is a diaphragm follower 60. This diaphragm follower is provided with a downwardly extending annular boss 61 which is provided with a socket 62 arranged to receive one end of a stem 63. The opposite end of the stem 63 has a convex surface and operatively engages the control beam or lever 9 within a notch 64, having a concave surface, provided adjacent one end of the lever 9.

It will here be noted that the lower end of the stem 63 and the notch 64 are so shaped and arranged as to permit rocking of the lever 9 relative to the stem without danger of causing any binding action between the stem and lever, thus eliminating any possibility of unwanted distortion of the diaphragm 5.

At the opposite side of the diaphragm 5 there is a chamber 65 which is in constant open communication with a passage and pipe 66 which may lead to a controlling means (not shown) located at any desired control station, and which may be of any desired type arranged to supply fluid under pressure to and release fluid under pressure from chamber 65 to provide any desired degree of controlling pressure therein.

At the upper face of the diaphragm 4 there is a chamber 68. Contained in this chamber and engaging the upper face of the diaphragm is a diaphragm follower 69. This follower has a stem 70 which is screw-threaded for a portion of its length and which projects through a central opening in the diaphragm and through a central opening in a diaphragm follower 71 contained in chamber 6 and engaging the opposite side of the diaphragm. A nut 72 provided on the end of the stem 70 within chamber 6 is tightened against the follower 71 thereby securing the followers 69 and 71 and diaphragm 4 together.

The upper casing section 2 is provided with an axial bore 73 which is lined with a fixed sleeve like member 74 which is open at its lower end to the pressure chamber 68 located above the diaphragm 4 and which is closed at its upper end by a wall 74a. The upper end of the member is provided with an exterior annular lug 74b which

engages a stop shoulder 75 provided in the casing, such engagements insuring the proper positioning of the sleeve member. Above the chamber 68 and surrounding the sleeve like member 74 is a chamber 76 which is in constant open communication with a fluid pressure control pipe 77 leading to a device (not shown) to be controlled. The chamber 76 is also connected to chamber 68 through a stabilizing choke 78 provided in a wall 79 of the casing section 2.

The upper face of the diaphragm follower 69 is provided with a central, upwardly projecting hollow stem 80 which extends through a short wear bushing 81 interposed between the stem and a portion of the lower inner wall of the sleeve like member 74. Pressed into the upper and outer end of the stem 80 is a guide member 82 having an enlarged portion 83 which is mounted to slide in the upper and adjacent end of the inner wall 20 of the sleeve like member 74. The guide member 82 is provided with an axial bore 84 which is open at its lower end through a release port in a release valve seat 85 to a chamber 86 in the diaphragm stem 80.

Above the guide member 82 and within the sleeve like member 74 there is a chamber 88 which is in constant open communication with the chamber 76 by way of passages 89 provided in the sleeve like member 74.

The chamber 88 is connected to a passage 90 leading to a chamber 91 which is in constant open communication with a passage and pipe 92 leading to a source of fluid under pressure (not shown). The chamber 91 is defined by the upper wall 74a of the sleeve like member 74, the casing section 2 and a cap or cover member 93 having screw-threaded engagement with the casing section 2. Contained in chamber 91 is a supply valve 94 which is adapted to be operated to control communication through passage 90, which valve is normally held seated, closing communication through passage 90, by means of a spring 95 also contained in chamber 91.

The valve 94 is provided with a fluted stem 96 which extends through the passage 90 into chamber 88 where it is provided with a release valve 97 which is so formed and arranged as to cooperate with the release valve seat 85, in a manner hereinafter described, to control communication between chambers 86 and 88.

A stem 99 is provided for operatively connecting the free end of the control lever or beam 9 to the diaphragm 4. This stem, at its lower end engages the free end of the control lever or beam 9 within a notch 100. The stem extends upwardly through an axial bore 101 in the diaphragm follower 68 and at its upper end engages a web 102 provided in the lower end of the diaphragm stem 80, which web is located just above the upper surface of the diaphragm follower 69.

It will be noted that opposite ends of the stem 99 are suitably shaped to engage the concave surfaces of the notch 100 and the web 102, so that no binding action between the lever 9 and the stem will result from rocking movement of the lever 9.

Operation

Assuming the nut 35 and thereby the frame member 21 of the relay valve device are positioned as shown in the drawing and that the pipe 66 and thereby the chamber 65 above the diaphragm 5 are devoid of fluid under pressure. Under these conditions the several other operating parts of the relay valve device will be in the

position in which they are illustrated in the drawing. With the diaphragm stem 80 thus positioned, the release valve seat 85 of the guide member 82 will be out of engagement with the release valve 97, and the spring 95 will maintain the supply valve 94 seated. With the supply valve 94 thus maintained seated, communication between chambers 91 and 88 is closed, and with release valve 97 unseated pipe 77 and connected chambers 76 and 68 are open to the atmosphere past said valve and through chamber 86 in the diaphragm follower stem 80, ports 86a in web 102, bore 101 in diaphragm follower 69, chamber 6 and passage 8.

If it is now desired to supply fluid under pressure to pipe 77, fluid under pressure is admitted to chamber 65 from a remote control station through pipe and passage 66. Fluid under pressure thus supplied to chamber 65 and acting on diaphragm 5 causes the diaphragm to move or deflect downwardly. The diaphragm 5 as it is thus deflected acts through the medium of diaphragm follower 69 and stem 63, to cause the lever 9 to rock in a clockwise direction about the fulcrum bar 20. The lever 9 as it is thus rocked shifts the stem 99 upwardly.

Upward movement of the stem 99 causes the diaphragm assemblage including diaphragm 4, diaphragm followers 69 and 71 and diaphragm follower stem 80 to move in the same direction. Upward movement of the stem 80 will be relative to the release valve 97 until the release valve seat 85 provided on the guide member 82 carried by the stem engages the release valve. Movement of the valve seat 85 into engagement with the release valve 97 cuts off communication between chambers 88 and 86, thus cutting off communication between chamber 88 and the atmosphere. Continued clockwise rotation of the lever 9 acting through the medium of the stem 99 and the diaphragm assemblage including diaphragm follower stem 80 will then move the release valve 97 with the stem 80 and the release valve will act to move the supply valve upwardly against the light biasing force of spring 95. As the supply valve 94 is thus moved upwardly it is moved out of engagement with its seat.

When the supply valve 94 is thus opened, fluid under pressure will flow from chamber 91 past said valve to chamber 88, and thence through ports 89 to chamber 76 from whence it flows to the control pipe 77. Fluid under pressure thus supplied to chamber 76 also flows through the stabilizing choke 78 to chamber 68 above the diaphragm 4. The stabilizing choke is provided to prevent the pressure in diaphragm chamber 68 increasing at a faster rate than the increase in the pressure of fluid in the control pipe 77.

The pressure of fluid thus supplied to chamber 68 acts on the upper face of diaphragm 4 and when the pressure of fluid in chamber 68 and consequently in the control pipe 77 becomes sufficient to overcome the pressure of fluid in chamber 65 acting on the beam or lever 9 through the medium of flexible diaphragm 5, follower 69, and stem 62, the diaphragm 4 will be caused to flex downwardly. As the diaphragm 4 flexes downwardly, the diaphragm follower stem 80 moves in the same direction, thereby permitting the spring 95 to seat the supply valve 94, without at the same time unseating the release valve 97. With the supply valve 94 seated, communication between chambers 91 and 88 will be cut off and there will be no further build up of pressure in chamber 88 and connected chamber 68 conse-

quently the diaphragm 4, followers 69 and 71, diaphragm follower stem 80 and lever 9 will come to a stop.

It will be noted that due to the position of the adjusting screw 35 and thereby the frame member 21 the central portion 19 of the fulcrum bar 20 engages the bearing surface of the lever 9 substantially intermediate its ends. With the fulcrum bar thus positioned, the lengths of the arms 10 of the lever 9 at opposite sides of the fulcrum bar will be equal and since the diaphragms 4 and 5 are of substantial equal areas it will be obvious that the pressure developed in the chamber 68 above diaphragm 4 and consequently in the control pipe 77 will be substantially equal to the pressure supplied to the diaphragm chamber 65 above diaphragm 5.

If it is desired to increase the pressure of fluid in pipe 77, fluid under pressure may again be supplied through pipe and passage 66 to chamber 65 to increase the pressure of fluid therein acting on diaphragm 5. The device will then operate in the same manner as above described to cause a corresponding increase in pressure of fluid in chamber 76 and pipe 77 and also in chamber 68 above diaphragm 4. It will thus be seen that the pressure of fluid in pipe 77 can be increased in such increments as desired by the provision of corresponding increments of control pressure in chamber 65, and the maximum degree of pressure may be provided in said pipe by providing a certain maximum pressure of fluid in chamber 65.

If it is now desired to reduce the pressure of fluid in pipe 77, fluid under pressure is released from chamber 65. When the pressure in chamber 65 acting on the right hand end of the lever 9 through the medium of diaphragm 5 and stem 63 is thus sufficiently reduced with respect to the opposing force of fluid under pressure in chamber 68 acting on the opposite end of the lever 9 through the medium of diaphragm 4, diaphragm followers 69 and 71 and stem 99, said opposing forces deflects diaphragm 4 downwardly causing the lever 9 to rock in a counterclockwise direction about the fulcrum bar 20. As the lever 9 is thus caused to rock counterclockwise about the bar 20, the diaphragm follower 69 and thereby the stem 80 is moved downwardly. This downward movement of the stem 80 will be relative to the release valve 97, since the supply valve 94 carried at the opposite end of the stem 99 is maintained in engagement with its seat by the pressure of spring 95. As a result, the release valve seat 85 provided on the guide member 82 carried at the end of the stem 80 will move out of sealing engagement with the release valve 97 to thereby open communication between chambers 88 and 86. With communication between chambers 88 and 86 established, fluid under pressure flows from chamber 88 and connected control pipe 77 and chamber 68 above diaphragm 4 to the atmosphere through the circuit hereinbefore traced. When the pressure of fluid in chamber 68 is thus reduced sufficiently with respect to the control fluid pressure in chamber 65, the latter pressure deflects diaphragm 5 downwardly. This downward deflection of the diaphragm 5 causes the lever 9 to rock clockwise about the bar 20 and thus through the medium 65 of the stem 99, moves the diaphragm follower 69 and attached stem 80 upwardly until the release valve seat 85 engages the release valve 97. This seating of the release valve 97 will prevent further flow of fluid under pressure from chambers 88 and 68 and pipe 77, thereby limiting the re-

duction in pressure therein to a degree corresponding to the reduction in pressure in the control fluid pressure acting in chamber 65.

If it is desired to effect a further reduction in pressure in pipe 77, a further reduction in pressure is effected in chamber 65, and the device will then operate to effect a corresponding reduction in pressure in said pipe in the same manner as above described. Upon a complete release of fluid under pressure from chamber 65, the diaphragm 5 and the lever 9 will move to and remain in the position in which they are shown in the drawing to allow a complete release of fluid under pressure from pipe 77.

It will now be seen that with the frame member 21 disposed as shown in the drawing, i. e., with the fulcrum bar 20 engaging the lever 9 at a point midway between its ends, the relay valve device is operative in accordance with any desired degree of increase or decrease in the pressure of control fluid in chamber 65 to cause corresponding variations in the pressure of fluid in pipe 77.

It will be understood that the pressure of fluid in chamber 68 required to produce the lap action of the supply and release valves may vary with relation to the pressure of fluid established in chamber 65, as determined by the relative lengths of the lever arms of lever 9.

It will be obvious that if the frame member 21 and thereby the fulcrum bar 20 is moved longitudinally of the lever in a direction away from the stem 63 the arm of the lever to which the diaphragm 5 is connected, will be correspondingly lengthened, so that it will require a greater fluid pressure in chamber 68 to overcome the pressure of fluid in chamber 65 than if the frame member were positioned as shown in the drawing. If, on the other hand, the frame member 21 and thereby the fulcrum bar 20 is moved in the direction toward the stem 63 the effective length of the arm is reduced and as a consequence a lesser pressure in chamber 68 will overcome the pressure of fluid in chamber 65 than is required if the frame member is positioned as shown.

In certain control systems it is desirable to control a relay valve device or the like jointly from two different control stations. For instance, on certain airplanes powered by two or more engines it is desirable when the speed of the engines are simultaneously controlled by the pilot, that the engineer be capable of adjusting the speed of one or more of the engines in order to synchronize all of the engines. The relay valve device embodying the invention is particularly adapted for this type of control. For example, one of these relay valve devices may be provided at the engineer's control station for controlling each engine on the plane. The pipe 66 may lead to the pilot's control station where suitable means may be provided for operation by the pilot to supply fluid under pressure to several pipes 66 simultaneously for thereby effecting operation of the devices to simultaneously adjust the speed of the several engines. If the engineer then finds it necessary to either increase or decrease the speed of any one or more of the engines to bring them into synchronism with the other engine or engines, he rotates the handle 55 either clockwise or counterclockwise, as the case may be, to adjust the position of the frame member 21 and thereby the fulcrum bar 20 relative to the lever 9.

It will be noted that when the handle 55 is rotated in a clockwise direction the frame member 21 and thereby the fulcrum bar 20 is moved, through the medium of the screw 35 relative to

the lever 9 in a direction toward the right-hand and that rotation of the handle in a counterclockwise direction causes the frame member 21 and thereby the fulcrum bar to move relative to lever 9 in a direction toward the left-hand.

Movement of the fulcrum bar 20 either to the right or to the left from the position in which it is shown at a time when fluid under pressure from pipe 66 is effective in chamber 65 and substantially the same pressure of fluid is also effective in pipe 77 and chambers 68 and 88, causes the device to operate in the same manner as above described to provide in said pipe and chambers 68 and 88 fluid at a pressure determined by the position of the fulcrum bar relative to the end of the lever 9 operative connected to the diaphragm 5. It will be noted that in this case the pressure of fluid obtained in pipe 77 is regulated by fluid under pressure supplied to chamber 65 and by manual control of the screw 35. The proper adjustment of screw 35 and thereby the fulcrum bar 20 will therefore provide any desired increase or decrease in pressure of fluid in pipe 77 relative to that obtained in response to pressure of fluid supplied to chamber 65.

From the foregoing it will be seen that I have provided an improved relay valve device which is arranged to be controlled by fluid under pressure from a remote station and which includes adjustable means manually operative for varying or modifying the pressure supplied by the device.

Having now described my invention, what I claim as new and desire to secure by Letters Patent, is:

1. A control valve device comprising a casing, in combination, valve means in said casing operative for at one time supplying fluid under pressure to a chamber in the casing and operative at another time for venting fluid under pressure from said chamber, a flexible diaphragm mounted in said casing subject to the pressure of fluid in said chamber for operating said valve means to vent fluid under pressure from said chamber, a rockable lever operatively associated at one end with said flexible diaphragm and at the opposite end with another flexible diaphragm, a control chamber, said other flexible diaphragm being responsive to an increase in pressure of fluid in said control chamber to rock said lever to effect operation of said valve means to provide a corresponding increase in pressure of fluid in the first mentioned chamber, the first mentioned diaphragm being responsive to the pressure of fluid supplied to the first mentioned chamber for opposing the rocking movement of said lever, a fulcrum about which said lever rocks, a frame member provided with a stem and arranged to carry said fulcrum, said frame member being shiftable longitudinally of said lever for varying the leverage ratio of said lever, a member having screw-threaded engagement with said casing and at one end engaging said frame member, means associated with said stem and said member for at all times maintaining said one end of said member in engagement with said frame member, and a handle carried by said member operative to rotate said member for shifting said frame.

2. A control valve device comprising a casing, in combination, valve means in said casing operative for at one time supplying fluid under pressure to a chamber in the casing and operative at another time for venting fluid under pressure from said chamber, a flexible diaphragm mounted in said casing subject to the pressure of fluid in

said chamber for operating said valve means to vent fluid under pressure from said chamber, a rockable lever operatively associated at one end with said flexible diaphragm and at the opposite end with another flexible diaphragm, a control chamber, said other flexible diaphragm being responsive to an increase in pressure of fluid in said control chamber to rock said lever to effect operation of said valve means to provide a corresponding increase in pressure of fluid in the first mentioned chamber, the first mentioned diaphragm being responsive to the pressure of fluid supplied to the first mentioned chamber for opposing the rocking movement of said lever, a fulcrum about which said lever rocks, a frame mem- 15

ber arranged to carry said fulcrum and shiftable longitudinally of said lever for varying the leverage ratio of said lever, a member having screw-threaded engagement with said casing and at one end engaging said frame member, an extension provided at one end of said frame member, said extension projecting to the exterior of said casing through said member, spring means cooperating with said extension and said member for maintaining said member in engagement with said frame member, and a handle carried by said member operative to rotate said member for shifting said frame member.

GLENN T. McCLURE.
